(57) **CLAIM**

The ornamental design for an electronic vaporizer as shown and described.

DESCRIPTION

FIG. 1 is a perspective view of an electronic vaporizer of the present invention;

FIG. 2 is a front view of the electronic vaporizer of FIG. 1; FIG. 3 is a right-side view of the electronic vaporizer of FIG. 1;

FIG. 4 is a rear view of the electronic vaporizer of FIG. 1; FIG. 5 is a left-side view of the electronic vaporizer of FIG. 1;

FIG. 6 is a top view of the electronic vaporizer of FIG. 1; and,

FIG. 7 is a bottom view of the electronic vaporizer of FIG. 1.

The broken lines shown throughout the FIGURES are for the purpose of illustrating portions of the electronic vaporizer that form no part of the claimed design.
